DESIGN FOR A COMBINED PERFUME BOTTLE AND HOLDER THEREFOR

Ward P. Merner, New York, N. Y., assignor to Richard Hudnut, New York, N. Y., a corporation of New York

Application July 27, 1940, Serial No. 93,970

Term of patent 3½ years

To all whom it may concern:

Be it known that I, Ward P. Merner, a citizen of the United States, residing in the Borough of Manhattan, county, city, and State of New York, have invented a new, original, and ornamental Design for a Combined Perfume Bottle and Holder Therefor, of which the following is a specification, reference being had to the accompanying drawing, forming a part thereof.

Fig. 1 is a side elevation of a combined perfume bottle and holder therefor, embodying the new design, and

Fig. 2 illustrates a top plan view.

The dominant feature of the new design consists of the parts shown in full lines in the drawing.

I claim:

The ornamental design for a combined perfume bottle and holder therefor, as shown and described.

WARD P. MERNER.
